MASS SPECTROMETRY

Robert V. Langmuir, Pasadena, Calif., assignor to
 Consolidated Engineering Corporation, Pasadena, Calif., a corporation of California

Application May 25, 1942, Serial No. 444,491

7 Claims. (Cl. 73—18)

This invention relates to mass spectrometry, and particularly to methods and apparatus for recording a mass spectrum.

In general mass spectrometry involves conversion of a material under analysis into ions, segregation or separation of these ions into ion beams according to their mass-to-charge ratios, and measurement of the intensities of the respective ion beams. The rates of formation of the respective ions in said conversion process vary with a large number of factors, such as the nature and energy of the ionizing force as well as the amount and composition of the material being analyzed. In the analysis of a material existing in gaseous or vapor form for instance, the sample is generally ionized by bombardment with low velocity electrons at low pressure, the ions formed then being accelerated by an electric field and ions of different mass-to-charge ratios then being segregated and successively directed by the combined action of magnetic and electric focussing forces through a collector slit onto a collector where the ions discharge, thereby producing a series of ion currents which vary according to the intensities of the corresponding beam, or according to the rates of formation of the respective ions. The ion currents are usually measured by means of an ion collector circuit and meter.

All mass spectrometers commonly in use at the present time are of fixed apparatus geometry, that is, the dimensions and arrangement of the ionization chamber, electrodes, collector slit, etc., are constant during the measurement or recording of a given mass spectrum. These devices are sometimes operated in such a manner as to maintain the geometry of the magnetic and electric fields also fixed. While for simplicity I shall illustrate the application of my invention to mass spectrometers of fixed geometry, that is mass spectrometers having both apparatus and field geometry fixed, it is to be understood that my invention is also applicable to known form of mass spectrometers of changing geometry.

In all mass spectrometers in which ions of different mass-to-charge ratio are successively detected, the mass-to-charge ratio may be expressed as some power function of an independent control variable. In all mass spectrometers of fixed geometry commonly in use and utilizing segregating and focussing forces provided by a magnetic field H and an electric field produced by a voltage V , the mass-to-charge ratio m of ions travelling over a specific path and passing

through the collector slit is given by the following formula:

$$m = K \frac{r^2 H^2}{V} \quad (1)$$

where K is a constant depending on the construction and r is a linear dimension of the mass spectrometer. In a mass spectrometer of fixed apparatus geometry, r is held constant. In using mass spectrometers of fixed geometry, beams of ions of different mass-to-charge ratios are moved past the collector slit in a direction transverse to the velocity of the ions at the collector slit so that ions of different mass-to-charge ratio are successively focussed at the collector slit and detected at the collector. The movement of the beams past the collector slit may be accomplished by adjusting the electric and/or magnetic fields which cooperate in the separation and/or focusing of the ions. The velocity with which a beam moves past the collector slit position depends on the rate at which said field or fields are changed. This velocity will be referred to as the beam speed.

If the electric field is the control variable being changed, it can be shown from Equation 1 that the speed S , with which any given beam of ions moves past the collector slit is given by the equation:

$$S = \frac{m}{K H^2 r} \frac{dV}{dt} \quad (2)$$

or

$$S = \frac{r}{V} \frac{dV}{dt} \quad (3)$$

Similar equations apply if some other independent control variable is changed.

Due to numerous factors including various physical limitations of the dimensions of the mass spectrometer, the beams have finite widths at the collector slit. The intensity distribution of a beam as measured, for example, in terms of ionic charge density or electric current density in the beam varies from point to point in the beam. In general, the intensity of any one beam is proportional to the surface integral of the current density across any cross-section thereof, and in a mass spectrometer of fixed geometry, is proportional to the maximum charge density or maximum current density in the beam cross-section at the collector slit, said beam cross-section preferably being taken perpendicular to the central path of the beam at the collector slit. For brevity, in this specification, the percentage or relative distribution of ionic charge density or electric

current density in said last mentioned beam cross-section will be referred to as the beam shape.

Normally ion beams are of substantially the same width and shape when focussed at the exit slit regardless of the mass-to-charge ratio of the ions. However, the widths and shapes of some beams are abnormal due to peculiarities in the ionization process by which the ions comprising such beams are formed. When such ionization processes or the effects thereof on the ion beam are of interest, it is especially important to record the beam shapes in a characteristic way regardless of the mass-to-charge ratio of ions forming the beams being recorded.

A distinction is here made between the actual mass-to-charge ratio M of the ions which comprise a given ion beam, and the "virtual" mass-to-charge ratio m of ions which could if present, travel over a given path from the ionization chamber to the collector. The "virtual" mass-to-charge ratio is given by Equation 1, or some similar applicable equation. In this specification "actual" will be omitted when the actual mass-to-charge ratio is meant, but "virtual" will be used wherever the actual mass-to-charge ratio is not intended.

From Equation 1 it can be shown that the spacing between the centers of adjacent beams differing in mass-to-charge ratio by a unit amount and focussed at the exit slit decreases as the virtual mass-to-charge ratio increases. Thus beams comprising ions of low mass-to-charge ratio are readily resolved. However, at large mass-to-charge ratios where the spacing between centers of adjacent beams approaches the width of the individual beams, adjacent beams begin to merge and become difficult to resolve.

In general two methods have been used heretofore for measuring the intensities of ion beams successively detected in a mass spectrometer.

In the first, ion beams comprising ions of predetermined mass-to-charge ratios were successively focussed at the collector slit by manual control of either the magnetic or electric segregating force or both. When using this method, the collected ion current is measured by means of a suitable circuit and meter connected to the ion current collector, after each ion beam is brought to rest at the collector slit. To study the shape of any beam with this manual control system, a segregating force is set at a succession of values differing by small amounts and the corresponding collected ion currents measured. Such a method is slow, tedious, and cumbersome.

A second method which has been used heretofore has involved automatically varying the accelerating voltage as a linear function of time in a mass spectrometer of fixed geometry, and synchronously recording the ion current produced as each ion beam is moved past the collector slit. In this method

$$\frac{dv}{dt}$$

of Equation 3 is constant, and the respective ion beams move past the collector slit at a speed proportional to the mass-to-charge ratio of the ions comprising the respective beams. Due to the fact that time is required for the ion current collector circuit and meter to respond to the ion current, the rate at which the voltage can be changed is determined by the spacing between peaks corresponding to ions of the largest mass-to-charge ratio which are to be recorded when

the accelerating voltage is so varied as a linear function of time. As a result, in this system the recording speed is unnecessarily slow for ions of low mass-to-charge ratio, and the total time required for recording a mass spectrum is unnecessarily long. As will become apparent hereinafter, with this system ion beams having the same shape are not recorded as peaks of the same shape on the mass spectrogram in this automatic recording system.

According to my invention, ion beams of the same shape but comprising ions of different mass-to-charge ratios may be recorded as peaks of the same shape by varying as an exponential function of time a control variable (such as H or V) in terms of which the mass-to-charge ratio is a power function, and recording the detected ion current on a recording medium moving at constant speed past the recording point. If H or V is the variable, all beams are moved past the collector slit at the same speed. In any event, according to my invention, the time in which a mass spectrogram may be recorded is decreased as compared with methods heretofore used, by changing the control variable at such a rate that the ratio of velocity with which different ion beams are moved past a collector slit to the mass-to-charge ratio of the ions comprising said beams is an inverse function of the respective mass-to-charge ratios. For maximum recording speed consistent with high resolving power of beams comprising ions of large mass, I move the respective detected beams past the collector slit at speeds which are an inverse function of the mass-to-charge ratio of ions comprising the respective beams.

This application is a continuation-in-part of the patent application Serial No. 437,922, filed April 6, 1942, by Edmund E. Hoskins, and Robert V. Langmuir.

The principal object of my invention is to provide an improved system for automatically recording a mass spectrogram. Another object is to provide a rapid method of recording a mass spectrum throughout a large range of mass-to-charge ratios. Still another object is to record beams of a mass spectrum in such a manner that differences in recorded peak shapes represent differences in the intensity distribution in a cross-section of the individual ion beams at the collector slit.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

Referring to the drawings:

Fig. 1 is a schematic diagram of a mass spectrometer incorporating a control circuit and a recorder operated in accordance with my invention.

Figs. 2, 3, 4, 7, and 10 are drawings of peaks representing ion beams which may be measured under different conditions adopted in operating a mass spectrometer.

Fig. 5 represents graphs useful in explaining my invention.

Figs. 6 and 8 are schematic diagrams of control circuits.

Fig. 9 represents the response characteristic of my ion current reproducing system.

In Fig. 1 I have illustrated the application of my invention to a Dempster type mass spectrometer, adapted to the analysis of gaseous materials. A gas to be analyzed is flowed continuously from a sample region (not shown) through an inlet conduit 1, into an ionization chamber 3, and thence to a vacuum pump (not shown) through the discharge conduit 5. Electrons emitted from a heated filament 7 in the ionization chamber are directed in a beam along a line perpendicular to the face of magnetic pole 9 by the combined action of a magnetic field which is directed downward perpendicular to the plane of the drawing, and an electric field parallel to the magnetic field provided by suitable electrodes (not shown).

When these electrons encounter molecules of the gas, the molecules become ionized in a manner characteristic of the gas and dependent upon the conditions of ionization. The concentrations of ions of different mass-to-charge ratio thus formed may be measured and utilized in studying the properties of the gas and in analyzing its composition. Positively charged ions are accelerated toward first slit electrode 11 by action of a small electrical potential which maintains said first collimating electrode negative with respect to a pusher electrode 13 on the opposite side of the electron beam. Some of the accelerated ions pass through a narrow slit 15 in said first collimating electrode 11, and are thereupon accelerated by a large negative potential maintained between second collimating electrode 17 and said first collimating electrode. Some of the accelerated ions then pass through a second slit 19 in said second collimating electrode.

In an analysis the potential between electrodes 11 and 17 may be varied from several hundred volts to several thousand volts. Ions which do not pass through the slits of the two electrodes 11 and 17 strike the walls of the ionization chamber and there give up their charge. The rate at which ions of a particular mass-to-charge ratio pass through the slits 15 and 19 is a measure of the rate of formation of such ions in the ionization chamber, and is also a measure of the concentration of such ions present there.

Owing to the action of the magnetic field, positive ions passing through second slit 19, follow circular paths. To detect ions of predetermined mass-to-charge ratio a collector slit 22 is positioned on the circumference of a semi-circle 20 of radius r , and 180° from the midpoint between slits 15 and 19. The mass-to-charge ratio of any ions which are formed at a particular point in the ionization chamber with zero initial velocity, and which travel over the specific path 28, is given by the formula:

$$m = \frac{r^2 H^2}{2V} \quad (4)$$

where V is the ion accelerating voltage. The mass-to-charge ratio of ions which can travel over said path may be changed by changing the accelerating voltage.

In practice, due to the finite widths of slits 15, 19, and 22 and variations in the initial velocities of the ions, the ions which strike a particular point at the exit slit 22 do not all travel over the same path, nor over paths of the same radius. Ions of a predetermined mass-to-charge ratio formed at different points in the ionization chamber 3, or even at the same point with different initial velocities pass through slits 15, 17 at dif-

ferent angles forming a divergent ion beam. Beams comprising ions of different mass-to-charge ratios are focussed at different corresponding points 180° from the collimating slits 15 and 17. These beams may be successively focussed at the exit slit 22 by changing the accelerating voltage.

So long as the relative concentrations with which the ions are formed at different points within the ionization chamber, and the paths over which the ions travel in the analyzer tube 21 are the same, the percentage distribution of ionic charge density over a cross-section of the detected beam, for example at the position of the collector slit, is the same regardless of the mass-to-charge ratio of the ions. This will occur in a mass spectrometer of fixed geometry when different ion beams are focussed at the collector slit, and some ions of the actual mass-to-charge ratio comprising each beam travel from a particular point in the ionization chamber over a specific path, such as the center path represented by the semi-circle 20 in Fig. 1. (See Bleakney's theorem, "American Physics Teacher," 4, 23, 1936.) The apparatus geometry may be maintained fixed by keeping the dimensions of the apparatus constant; the magnetic field geometry may be maintained fixed by keeping the magnetic field constant; and the electric field geometry may be maintained fixed as beams of different mass-to-charge ratio are moved past the collector slit by proportionally varying the electric fields between the pair of electrodes 11 and 13 and the pair of electrodes 11 and 17.

While the ion detector described herein consists of an ion collector with an electrode having a collector slit therein mounted before it, other means for detecting the intensities of ionic charge in different sections in the cross-section of an ion beam can be readily provided. For example, a known form of narrow ion current collector alone without a collector slit electrode may be utilized.

Ions which travel over path 20 or any adjacent paths and which pass through collector slit 22, fall on ion collector 23, there give up their charge, and produce an ion current which passes through shielded lead 25 into upper input terminal 27 of D.-C. amplifier 29, and thence to grounded input terminal 30. The D.-C. current is applied to a galvanometer 41 after amplification by said D.-C. amplifier.

As the displacement of galvanometer mirror 50 from a neutral position is changed in response to changes in collected currents, the mirror displacement is optically amplified by means of light ray 51 from light source 53. The ray is projected onto a moving medium in the form of a strip of photographic paper 55 driven at constant speed by a motor 53. As the reflected ray is displaced in a direction perpendicular to the direction of paper movement, a latent image is automatically formed on the paper representing a plot of the collected current as a function of time. If the speed of the recording medium past the recording point is not constant, correction for this condition may be readily made. Simultaneously with the recording of the galvanometer current, light from source 59 is projected onto the photographic paper through slots 61 in mask 63, said slots lying in lines parallel to the direction of paper movement to provide indicia in the form of trace displacement scale lines 64. A visible mass spectrogram is obtained when the paper is developed.

In order to treat ion beams uniformly in the

recording system and thus to produce corresponding recorded peaks of uniform character on the mass spectrogram when the beams are of the same shape, regardless of the mass-to-charge ratio of the ions, I move each beam past the center of the collector slit at the same speed, preferably by varying the electric accelerating potentials to which the ions are subjected as an exponential function of time. Any deviation of the recorded peak shape from the normal will indicate an anomalous condition such as may be associated for instance with peculiar conditions sometimes arising in the ionization process where the ions sometimes start with abnormally high initial velocities. Since variations in the peak shape from the normal may be utilized in a study of the ionization process and in the identification of the gas producing the ions, it is important to reproduce the peak shapes in a uniform manner.

A control circuit utilized to achieve constant beam speed and hence uniform treatment of different beams may be in the form of a resistance R , condenser C , discharge circuit 31 . In this circuit resistance 32 provides a potentiometer having its positive end 33 connected to pusher electrode 13 , its negative end 35 connected to second slit electrode 17 through the metallic analyzer tube 21 and to ground and an intermediate point 34 near the positive end thereof connected to first collimator electrode 11 . Condenser 37 is connected across said resistance. Battery 38 having its negative pole grounded may be connected to potentiometer end 33 through switch 41 . After condenser 37 has been charged to a standard potential by closing key 41 , thus establishing predetermined positive potentials on electrodes 11 and 13 , said key may then be opened to discharge the condenser through potentiometer 32 , thus causing the potential differences between the electrodes 11 , 13 and 17 to decrease as an exponential function of time depending upon the time constant RC of the circuit rather than as the customary linear function of time. Thus, at a time t after opening key 41 the accelerating voltage for ions formed at any particular point in the ionization chamber is given by the equation

$$V = V_0 e^{-kt} \quad (5)$$

where k is the reciprocal of the time constants RC of the control circuit, and V_0 is the initial accelerating potential to which said ions are subjected.

As the potential differences between said electrodes 11 , 13 , and 17 decrease, beams comprising ions of larger and larger mass-to-charge ratio are successively focussed at collector slit 22 and directed against the ion collector 23 . As beams comprising ions of different mass-to-charge ratios are moved past the collector slit 22 , variations in the intensity of the collected current occur. In general, the magnitudes of these collected ion current variations correspond to the rates of formation of different corresponding ions. Expressed in other words, as beams of ions of different mass-to-charge ratios successively impinge said ion collector, a series of ion currents is produced in which the magnitude of each ion current corresponds to the rate of formation of ions of the corresponding mass-to-charge ratios in the ionization chamber and the variation of the ion current with time depends on the beam shape. A mass spectrum of the sample is obtained by measuring heights of the recorded peaks, or the intensities of the ion currents.

In order to fully appreciate the advantages of

operating a mass spectrometer in accordance with my invention, the effect of variations in the speed with which any one ion beam is moved past the exit slit 22 in a radial direction indicated by arrow 24 , will now be explained.

In order that the recorded peaks will not be sharp at the top and thus render the peak magnitude difficult to measure, I prefer to make the exit slit at least as wide as the beam width or the space occupied at the exit slit by most of the ions of a beam. If the beam is moved slowly past the exit slit, the detected ion current will be represented somewhat according to a curve such as that shown in Fig. 2A. If the beam is moved past the exit slit faster, the current will be detected for a shorter time, and will be represented by a curve such as that shown in Fig. 2B. In both Figs. 2A and 2B, the amplifier and recorder have been operated sufficiently slowly for each variation in detected current to produce a corresponding full indication on the galvanometer, and both of the recorded peaks are flat topped, thus simplifying accurate measurement of the ion current. However, if the beam is moved past the exit slit still faster, the amplifier and galvanometer may not react fast enough to produce a full indication of each variation of detected current and the recorded peak will be narrow and pointed somewhat as shown in Fig. 2C, even though the collector slit is wider than the beam. At a still greater speed, the maximum recorded displacement corresponding to the maximum value of the ion current will be abnormally low, as indicated in Fig. 2D. The maximum attainable value may be approached to any given degree of accuracy by moving the beam past the exit slit sufficiently slowly. To record at a speed corresponding to Fig. 2D would produce a recording which could not be easily used for accurate determination of beam intensities. However, to record at a speed corresponding to Fig. 2A would waste time. In practice a suitable intermediate speed is determined empirically by recording at different speeds and selecting a speed suitable for the purpose at hand. The beam speed necessary to achieve any given degree of accuracy depends on both the beam width and slit width. To measure ion currents to an accuracy of about 0.5 to 1%, I prefer to utilize a beam speed which is just sufficiently great for the recorded peak to reach within a small amount, preferably about 0.25% of 1% of its maximum attainable value.

If the exit slit is very narrow compared to the width that a beam has in the plane of the exit slit so that only a small cross-section of a beam is detected at any instant, and beams of different mass-to-charge ratios move past said slit at a very slow speed, and the amounts of ions passing through unit area of this narrow slit per second are measured, then a graph such as that shown in Fig. 3 may be constructed representing a plot of the collected current as ordinate against the "virtual" mass-to-charge ratio m as abscissa. At each instant the collected current is equal to the current density in the beam integrated over the area of the collector slit. As a matter of fact all the ions producing any recorded peak P , are of the same actual mass-to-charge ratio, and the distance between centers of any two peaks on this graph is a multiple of one unit of mass-to-charge ratio. If the beams were sharply defined and of uniform intensity, the sides of the peaks are parallel to the current axis and the corners of the peaks at the top and bottom are right angles instead of being rounded as shown.

As shown hereinabove, if ions of different mass-to-charge ratios corresponding to the different peaks are formed in the ionization chamber in the same proportion at different points thereof and passed through slits 15 and 19 of fixed dimensions, then, while electric potentials acting on the beam are varied in constant proportions, beams of ions having initially zero or negligible velocity at the points of ionization (which is normally the case) will be of the same size and shape when focussed at the collector slit. The normal width of such a beam at the exit slit is independent of the field strengths and may be determined from the widths of slits 15 and 19, the distance between electrodes 11 and 17, and the field strengths. Whereas the widths of the beams at the collector slit will normally be the same, the width of peaks in the graph of Fig. 3 will be very nearly proportional to the mass-to-charge ratios of the ions forming the corresponding beam. For heavy ions, the plotted peaks begin to merge and for still heavier ions they actually overlap because the interval between centers of successive beams becomes less than the beam width.

In practice with a Dempster type mass spectrometer individual recorded peaks are slightly asymmetrical as shown in Fig. 10 due to asymmetry of the ion beam at the exit slit.

If we introduce the variable X , such that

$$dX = \frac{dm}{m} = kdt \quad (6)$$

where t represents time, and k is a constant, then the height of any peak at any point thereof may be represented as a function $D(X)$. Since the peak displacement actually represents an electric current which is detected by the ion collector, and the intensity of the detected current varies as a function of time t , this current may be represented as the sum of sinusoidal current components of angular frequency ω . If the origin of X is at the center of any one peak corresponding to the actual mass-to-charge ratio m , as indicated in Fig. 4, the formula of that peak may be represented as:

$$D(X) = \int_{-\infty}^{+\infty} g(\omega) e^{i\omega X} d\omega \quad (7)$$

where $g(\omega)$ represents the Fourier transform of $D(X)$, or the frequency spectrum of the ion current. This transform is defined by the equation:

$$g(\omega) = \frac{1}{2\pi} \int_{-\infty}^{+\infty} D(X) e^{i\omega X} dX \quad (8)$$

(See Guillemin, "Communication Networks," chapter XI, John Wiley, (1935).)

All normal peaks will have the same width and shape but will differ in height when plotted to the coordinates of Fig. 4. For beams of normal shape the function $g(\omega)$ will always be the same except for a multiplying factor proportional to the peak height. The Fourier transform $g(\omega)$ is characteristic of any peak whether it be of normal or abnormal shape. Equation 7 will represent the actual shape of the recorded peak provided the apparatus responds uniformly to all frequency components ω making any substantial contribution to the ion current. This will be true, for example, if the collector slit is very narrow compared to the beam width and the amplifier and galvanometer respond instantaneously to the detected ion current. However, the apparatus may not respond uniformly to all such frequency components, since the collector slit itself may be wide enough to modify the characteristic of the

ion current and the combination of amplifier 29 and galvanometer 47 is in fact a current transducer which has a finite time constant and may modify the proportions of the contributions of the different frequency components of any detected ion current to the actual recorded peak. If the width of the collector slit through which the beam passes is constant and large enough to modify the peak shape, the formula for the current to the ion collector may be represented as

$$I(X) = \int_{-\infty}^{+\infty} B(\omega) g(\omega) e^{i\omega X} d\omega \quad (9)$$

where $B(\omega)$ is a characteristic depending on the exit slit width and the speed of the beam past the exit slit. The product $B(\omega) g(\omega)$ is the Fourier transform of the ion current to the collector, or the rate of discharging the beam at the collector, and varies from one beam to another only if they are of different shapes. This current will be recorded as a peak represented by the formula

$$D'(X) = \int_{-\infty}^{+\infty} C(\omega) B(\omega) g(\omega) e^{i\omega X} d\omega \quad (10)$$

where $C(\omega)$ is a transducer characteristic depending on the electrical characteristics of the D.-C. amplifier and the electrical and mechanical characteristics of the galvanometer. Fig. 9 shows one such characteristic $C(\omega)$ in which all frequency components

$$\left(f = \frac{\omega}{2\pi} \right)$$

of any ion current up to 4 cycles per sec. are reproduced substantially uniformly by the amplifier and galvanometer; above 4 cycles per sec. all components are attenuated in various amounts increasing with frequency. At about 10 cycles per second $C(\omega)$ is 0.70 of its maximum value. Expressed in other words, the time constant T of the transducer is 0.1 sec. It follows that if the "virtual" mass-to-charge ratio is varied in accordance with Equation 6, that is according to the equation

$$m = m_0 e^{kt} \quad (11)$$

where m_0 is the virtual mass-to-charge ratio of ions detectable at time $t=0$, all beams having the same shape will be recorded as peaks of the same shape regardless of the slit width, and the shapes of recorded peaks will differ only if the Fourier transform $g(\omega)$ corresponding to said peaks differ.

I have found that a mass spectrometer of fixed geometry will uniformly reproduce beams of the same shape, if the accelerating voltage V is either increased or decreased as an exponential function of time. With the control circuit of Fig. 1 the voltage is decreased in accordance with the exponential function of time expressed by Equation 5. When the voltage varies exponentially, the instantaneous velocity with which ions traveling over the semi-circular path 20 move radially past the center of the collector slit is the same regardless of the mass-to-charge ratio of the ions and is given by the equation

$$S = kr \quad (12)$$

In this case the operation may be described simply by saying that the speed of each beam is the same as it passes the collector slit. Recorded peaks bearing a uniform relation to the ion beam shapes will be produced as long as this condition is maintained during the recording of the respective peaks so that, as a matter of fact, the voltage may, if desired, be changed between peaks more

rapidly than indicated by Equations 5 and 12. The recorded peaks will reach their maximum attainable value if $B(\omega)$ and $C(\omega)$ or their product are uniform for each peak in the frequency range in which $g(\omega)$ is large.

In Fig. 5a, the straight line a plot of $\log V$ against time represents Equation 5. In Fig. 5b, the straight line a' is a similar and corresponding plot of $\log m$ against time and represents Equation 11. The constant slope of these curves indicates the constancy of the ion beam speed at the exit slit. Curves b and b' in these figures represent cases in which the beam speed varies as an inverse function of the mass-to-charge ratio. In both cases represented in these figures the ratio S/M of beam speed to mass-to-charge ratio is an inverse function of mass-to-charge ratio, that is, in the range of operation this ratio S/M decreases as the mass-to-charge ratio increases.

In a preferred form of control circuit which is shown in Fig. 6, the high voltage end of a regulated power supply 11 is connected through two resistances 13 and 15 to the accelerating voltage control potentiometer 32. Said potentiometer is connected to electrodes 11, 13 and 17 in the same manner as potentiometer 32 shown in Fig. 1. In the present case a vacuum tube 17 is connected with its anode 79 and cathode 81 in shunting relation across one of said resistors 15 and potentiometer 32. A control circuit in the form of a resistance condenser discharge circuit 31' is connected between grid 83 and filament type cathode 81 of tube 17. A condenser 85 connected across potentiometer 32 cooperates with resistance 15 and said potentiometer to filter out any fluctuations in voltage that might appear across said potentiometer 32 due to the presence of any ripple in the filament 81 current. In this circuit the resistance of the RC circuit is in a low voltage section of the apparatus and may therefore be several megohms, thus facilitating provision of a time constant of several minutes or more. With this circuit the beam speed may be varied if desired during the recording by taking advantage of the non-linear characteristics of the vacuum tube.

In Fig. 8 I have illustrated schematically a resistor condenser discharge control circuit 31'' by means of which the voltage is changed and the speed k_r with which a beam is swept past the collector slit may be varied during the recording in any desired manner. The beam speed may be controlled by varying one of the elements of the resistance condenser discharge circuit 31'', such as the resistance 32' as a suitable predetermined function of time or virtual mass-to-charge ratio by means of a suitably shaped motor driven cam 81, the operation of which is initiated in any convenient manner in timed relation to the moment that key 41 is opened to initiate the discharge of the condenser 37'.

When peak shapes due to beams comprising ions of different mass-to-charge ratios are to be compared, the beam speed should be the same when recording the two corresponding peaks. However, if fidelity of reproduction of the respective beams is not required, but it is only desirable to measure the intensity of each of the beams, the beam speed can be made more rapid where the spacing between peaks is less than or equal to the peak widths, and reduced for peaks which are closer together. Plots of curves corresponding to such speed changes are shown at b and b' in Figs. 5a and 5b. For both curves the time rate of change of the logarithm of the "virtual" mass-to-charge ratio divided by the "vir-

tual" mass-to-charge ratio is an inverse function of the "virtual" mass-to-charge ratio. The beam speeds suitable for any purpose with mass spectrometers of different dimensions or with a mass spectrometer of changing dimensions are proportional to a linear dimension of the mass spectrometer.

Thus when uniform reproduction of beam shapes is not required, there is some advantage to be obtained by varying the beam speed as an inverse function of the mass-to-charge ratio of the ions. If the peaks of lower mass-to-charge ratio are being recorded at a high speed satisfactorily consistent with accuracy, then at high masses where the peaks are crowded close together, that is, where the distance between sides of peaks is less than the peak widths, one peak may start to impinge the collector before the amplifier and galvanometer have had sufficient time to return to the neutral condition. This would produce a mass spectrum such as that shown in Fig. 7, wherein the valleys v between adjacent peaks p do not reach the zero displacement axis cd , even though the detected ion current may have reached a zero value momentarily. According to my invention the galvanometer may be returned to its zero position at such high masses by reducing the beam speed at the exit slit when detecting ions of high masses. When changing the ion beam speed in this manner, beams of the same shape are not recorded as peaks of the same shape. However, this does simplify the measurement of the maximum amount of ion current due to beams comprising ions of different high mass-to-charge ratios.

If the beam is sharply defined and of uniform intensity distribution in a beam cross-section at the collector slit, it can be shown that the fractional amount by which the recorded peak fails to achieve its maximum attainable value is given approximately by the following equation:

$$\Delta = \frac{ST}{a} e^{-\frac{b}{ST}} \left(1 - e^{-\frac{a}{ST}} \right) \quad (13)$$

where $b > a$ and the beam and collector slit widths are either a and b respectively or b and a respectively, as the case may be. From Equation 13 it is apparent that the beam speed S required to produce a given degree of accuracy as expressed in terms of Δ depends on both the beam width and the collector slit width, as well as the response time T of the ion current transducer. If $a \ll b$, the velocity of the beam should be

$$S \leq \frac{b}{6T} \quad (14)$$

for the recorded amplitude to come within about 0.25 of 1% of its maximum attainable value.

I have found experimentally that when the beam shape is similar to that shown in Fig. 10 and the beam and collector slit widths are about the same, a beam speed of about 10% of the value computed from Formula 14 gives a high degree of accuracy in analysis of mixtures.

In practice, for maximum recording speed each beam is moved past the collector slit at a speed below that for which any harmful effects begin to appear due to failure of the recorder either to produce maximum indication of the ion current or to accurately reproduce the beam shape according to the purpose at hand. In all cases the ratio of beam width to collector slit width should be maintained less than about unity to assure normally achieving flat top peaks.

It is thus seen that I have provided a flexible system in which the beam speed may be controlled in any suitable manner such as may be required for example to achieve uniform reproduction of ion beams or maximum recording speed.

I claim:

1. In a mass spectrometer of fixed geometry, an ion detector, a control device adapted to successively move beams comprising ions of a different mass-to-charge ratio transversely to and in contact with said detector at speeds which vary as an inverse function of mass-to-charge ratio of the respective ions, and an ion current recorder connected to said detector.

2. In mass spectrometry involving the production of a plurality of ion beams of substantially the same shape but different mass-to-charge ratios by propelling the ions with an accelerating voltage through a magnetic field and longitudinally along the beams successively onto an ion detector while shifting the beams with respect to the detector and transversely to the direction of ion travel, the improvement which comprises shifting the beams with respect to the detector by varying as an exponential function of time a factor selected from the group consisting of the magnetic field and the accelerating voltage.

3. Process according to claim 2 in which each ion beam is shifted transversely with respect to the detector at the same speed.

4. Process according to claim 2 in which the

factor is varied at a rate such that the ratio of velocity with which different ion beams are shifted transversely to the detector to the mass-to-charge ratio of the ions comprising the respective beams is an inverse function of the respective mass-to-charge ratios.

5. Process according to claim 2 in which the respective ion beams are shifted transversely to the detector at speeds which are an inverse function of the mass-to-charge ratio of ions comprising the respective beams.

6. In a mass spectrometer, the combination which comprises means for producing a plurality of ion beams of different mass-to-charge ratios including means for producing a magnetic field and electrodes for impressing an accelerating voltage upon the ions to propel them in the field, an ion detector, means for bringing the beams successively into contact with the detector by shifting the beams transversely to the direction of ion travel and means for controlling the rate of the shifting by varying, as an exponential function of time, a factor selected from the group consisting of the accelerating voltage and the intensity of the magnetic field.

7. Apparatus according to claim 6 in which the means for controlling the rate of shift includes a control circuit with a condenser, a resistance, and means for discharging the condenser through

30 the resistance.

ROBERT V. LANGMUIR.
